UNITED STATES PATENT OFFICE.

MILO J. JOHNSON, OF McBRIDES, MICHIGAN.

MUSIC-LEAF TURNER.

1,235,807.

Specification of Letters Patent.

Patented Aug. 7, 1917.

Application filed June 7, 1916. Serial No. 102,243.

To all whom it may concern:

Be it known that I, MILO J. JOHNSON, a citizen of the United States, residing at McBrides, in the county of Montcalm, State of Michigan, have invented certain new and useful Improvements in Music-Leaf Turners; and I do hereby declare the following to be a full, clear, and exact description of the invention, such as will enable others 10 skilled in the art to which it appertains to make and use the same.

This invention relates to music leaf turners and has for an object the provision of an appliance or mechanism designed for 15 universal adaptation and by which the sheets of a music score may be conveniently turned. In carrying out the invention it is my purpose to provide a music leaf turner which shall embody a mechanism of novel construction and arrangement by which music sheets 20 may be readily turned to expose one or the other of their sides, and by which the music sheets may be furthermore turned simultaneously in one direction when it is desired to 25 repeat the score.

The invention further proposes a music leaf turner which shall comprise a frame readily applicable to a music rack or stand of ordinary construction, and which shall 30 further include a plurality of leaf turning elements operatively connected with a turning mechanism of novel construction, arrangement and operation.

With the above and other objects of similar nature in view the invention consists in the combination, construction and arrangement of parts, set forth and falling within the scope of the appended claims.

In the drawings:

40 Fig. 1 is a front elevation of the improved device in set-up position;

Fig. 2 is a vertical sectional view taken on the line 2—2 of Fig. 1;

Fig. 3 is a section taken on the line 3—3 of 45 Fig. 1;

Fig. 4 is a view similar to Fig. 3, illustrating the operation of the device;

Fig. 5 is a section taken on the line 5—5 of Fig. 1;

50 Fig. 6 is a detail section taken on the line 6—6 of Fig. 1;

Fig. 7 is a fragmentary elevation of a portion of the actuating mechanism, and

55 Fig. 8 is a bottom edge view of what is shown in Fig. 1.

Referring now more particularly to the

accompanying drawings, the invention is shown generally at 10 and comprises two skeleton frame sections 11 and 12 respectively, which sections are hingedly connected together as at 13 whereby they may be readily folded to dispose the device in relatively compact form when not in use. 60

Stretched across each of the sections 11 and 12 at spaced intervals are wires 14 65 against which the sheets of a music score are adapted to rest, while said sections are furthermore provided with spring clips 15 arranged to clamp the back sheets of the score against displacement from the sections. The 70 section 11 is further provided adjacent one end with a relatively wide backing strip 16 arranged transversely thereof and suitably secured in any desired manner. For holding the sections in set-up position there is pivoted to the rear face of the backing strip a latch element 17, a pin 18 being carried by the adjacent side of the section 12 for detachable engagement by said element. 75

For turning the several loose sheets of the 80 music score, there is provided a plurality of similarly constructed turning elements 19, each consisting preferably of a single length of wire bent to coincide with the top, bottom and outer side portions of the sections. 85 These elements are hingedly carried by the section 11, an end portion of each being directed inwardly of said section as indicated at 20 and journalledly engaged in suitable bearings 21 carried by the section and by the 90 backing strip 16. The other end portions of the turning elements terminate in eyes 22 pivotally engaged about the inwardly directed ends of the other element outwardly of the section. 95

Fixed to the terminals of the inwardly directed portions 20 of the turning elements are pinions 23.

For actuating the turning element the following mechanism is employed. Secured 100 to the front face of the backing strip are spaced plates indicated respectively at 24 and 25. These plates are each provided with a pair of outwardly directed ears 26, having formed therein a pair of openings 27, said 105 openings alining with respective openings in the corresponding ears of the other plate.

Slidably engaged through alining openings in corresponding pairs of ears 26 are relatively movable rods 28 and 29, the former being provided at one end with a rack 30 meshing with the pinion 23 on the related 110

turning element whereby when said rod is moved in one or the other direction, said turning element will also be moved in a corresponding direction. Encircling the rods 5 28 are spaced pairs of coil springs 31 fixedly connected at their outer ends to the rods while their inner ends are free to move therein. Carried by each of the rods 29 intermediate its ends is a yoke member 32 the 10 legs of which embrace the rod 28 between the springs 31. Said yoke is movable with the rod 29 in a manner to be described whereby to compress one or the other of the springs 31 and consequently force the rod 15 28 in a corresponding direction to actuate its turning element.

For operating the rods 29 there are pivot- 20 ed as at 33 to the plate 24, bell crank levers 34, the arms of which are respectively connected with the rods 29 and, through the medium of links 35, with the actuating ele- 25 ments 36 and 37. For mounting the elements 36 and 37 on the backing strip 16, there is secured to the outer face of the latter a plate 38 provided at its ends with laterally turned ears 39 having alined bearing openings 40 formed therein. The element 36 comprises a sleeve 41 journaled in said bearing openings 40 while the element 30 37 consists of a rod 42 rotatably engaged through said sleeve, the inner ends of the elements being connected as at 43 to the respective links 35 while carried at their outer ends are finger pieces 44 each consisting of oppositely directed arms 45 termin- 35 ating in push buttons 46.

Thus by pressing the top button of the elements 37 and 36 in order, the loose sheets of music are turned in one direction, while 40 by pressing upon the lower buttons in order the sheets may be returned to their initial position. Should it be desired to repeat the entire music score the loose sheets may be simultaneously turned to their initial position by pressing upon the lower button of 45 the element 37, there being carried by the arm of said button a lateral extension 47 overlying the lower arm of the element 36 so that when said element 37 is actuated the element 36 will likewise be moved.

For securing the loose sheets of the music score to the turning elements there are fixed to the sides thereof spaced fingers 48 while coöoperating with said fingers are spring 55 pressed clamping members 49 each consisting preferably of a single length of wire bent into substantial U-shape with their legs looped to pivotally receive the elements and terminating in lateral extensions 50, yield- 60 ably held in clamping relation with the fingers. The turning elements further carry at their upper sides spaced arms 52 between which the upper edge of the loose sheets are removably received.

65 It will be understood, when moving the

rods 29 to compress either of the springs 31, that it is necessary to retain said spring compressed until the related turning element has been given sufficient impetus to complete its movement in the corresponding direction. 70 In order to accomplish this there is carried by the plate a pair of upstanding lugs 53 each carrying a leaf spring 54 secured intermediately thereto and having its ends engaged frictionally with the related rod 29, 75 said rod being provided with spaced notches 55 adapted to receive one or the other end of the spring whereby it will be held at its limit of movement in either direction.

For releasing the rod 29 after the turning 80 element has been carried beyond its center of movement, there is provided on the opposite end of the rod 28 from the rack 30 a U-shaped clip 56 straddling the rod 29 between the ends of the spring 55. 85

Thus as the rod 28 is moved under the influence of the compressed spring 31, to actuate the turning element, the clip 56 moves also with the rod to carry one of its legs between the rod 29 and one or the other end 90 of the spring 31, said end being in this manner disengaged from the notch so that the rod 29 will be free to move in the opposite direction to compress the other of the springs. 95

What is claimed is:

1. A music leaf turner comprising a frame, a leaf carrying element hinged to the frame, relatively movable rods carried by the frame, means resiliently connecting 100 said rods, operative connections between one of the rods and said carrying element, means for actuating the other of said rods, and means for locking said last named rod at its limit of movement in both directions, said 105 means being releasable by the first named rod.

2. A music leaf turner comprising a frame, a leaf carrying element hinged to the frame, relatively movable rods carried by 110 the frame, operative connections between one of the rods and said carrying element, spaced springs encircling said rod, means carried by the other rod interposed between said springs, means for actuating the last 115 named rod to compress one or the other of said springs, means for locking the second rod at its limit of movement in either direction, and means carried by the first named rod for releasing said locking means. 120

3. A music leaf turner comprising a frame, a leaf carrying element hinged to the frame, a rod operatively connected with the carrying element, springs engaged with the rod, and a single means by which the springs 125 are alternately compressed to impart through their expansive tendency movement in opposite directions to the rod and correspondingly actuate the carrying element.

4. A music leaf turner comprising a 130

frame, a leaf carrying element hinged to the frame, a rod operatively connected with the carrying element, spaced springs engaged with said rod, means for compressing one or the other of said springs to move the turning element in opposite directions, means for locking the first named means when the springs are compressed and means for releasing said locking means.

10 5. A music leaf turner comprising a frame, a carrying element hinged to the frame, a rod operatively connected with the carrying element, spaced springs encircling

the rod, a yoke embracing the rod between the springs, means for moving the yoke in 15 opposite directions to compress one or the other of said springs and consequently actuate the turning element in a corresponding direction.

In testimony whereof, I affix my signature, in the presence of two witnesses.

MILO J. JOHNSON.
